Specification of Letters Patent.

Patented Mar. 28, 1916.

Continuation of application Serial No. 711,326, filed July 24, 1912. This application filed June 25, 1913. Serial No. 775,738.

To all whom it may concern:

Be it known that I, THOMAS LUND, a citizen of the United States, residing at Beverly, in the county of Essex and State of Massachusetts, have invented certain Improvements in Compressing-Machines, of which the following description, in connection with the accompanying drawings, is a specification, like reference characters on the drawings indicating like parts in the several figures.

The invention of this application, which is a continuation of an application Serial No. 711,326, filed July 24, 1912, relates to compressing machines and more particularly to a type of machine used for compressing boot or shoe parts, such as heels, heel lifts or soles. In machines of this character it is usual to insert the blank or article to be compressed in a feeding device, which automatically carries the article to a sectional compressing mold consisting of a plurality of relatively movable dies constructed in a manner to permit the mold to be opened for the reception of the article or blank fed to it. After the blank is deposited in the mold the sections of the latter are moved toward each other to apply pressure to the blank. After the blank has been compressed the mold is again opened and suitably timed ejecting mechanism comes into play to remove the compressed blank from the mold in order to clear the space for the reception of a fresh blank. The bottom member of the compressing mold has been formed as a movable plate supported upon a spindle which was actuated automatically to lift the plate in the mold when the compressed blank was to be discharged from the mold. The timing of the movements of the plate relative to the feeding mechanism was such that the plate was elevated to a position in which its top surface was flush with the top of the mold in time to permit the compressed blank to be pushed off the plate by the feeding mechanism as it advanced to bring a fresh blank into position to be delivered to the mold. The incoming blank was released by the feeding mechanism and deposited upon the plate while the latter was still in its ele-

vated position. The plate with the blank upon it was then lowered into the mold, after which the mold was closed upon the blank and the blank compressed.

When handling thin flat blanks of comparatively large area, such as sole blanks, and depositing them in a mold which may be somewhat shallow the method above described is not certain in operation, since mechanical considerations in the design of the machine limit the amount of lateral opening which may be allowed the mold and, especially when a warped or misshapen blank is deposited upon the discharging plate, the blank is likely to be displaced laterally to such an extent that it will not descend into the mold properly with the plate upon which it rests. The consequence of this is that a portion of the edge of the blank is likely to be sheared off.

An object of the present invention is to provide mechanism for handling a blank which shall introduce the blank into the mold with ease and certainty, thus avoiding the difficulty mentioned. I do this by so timing the movements of the mold, the blank discharging mechanism, and the feeding mechanism that the discharging device is retracted prior to the release of an incoming blank by the feeding mechanism and the incoming blank is delivered to the mold while the mold cavity is open approximately to its full extent.

To this end an important feature of the invention consists in the provision, in a machine of the kind mentioned, of means—preferably a plate normally forming the bottom of the mold but independently movable therein—for discharging a compressed blank from the mold and actuating mechanism arranged to move the discharging means to discharge a compressed blank and to retract, at least partially, said means prior to delivery of another blank to the mold by the feeding mechanism. The retraction of the discharging plate preferably occurs during the movement of the feeding mechanism, which is most advantageously arranged for movement simultaneously with the ejecting devices which eject or remove the compressed blank from the machine. In

the specific embodiment of the invention hereinafter described and illustrated in the accompanying drawings, the plate is vertically movable independently of the side dies or sections of the mold and is raised and held up in discharging position until the heavier portion of the blank has been pushed off. In order to secure the best possible operation of the machine, the lowering of the plate into normal position may begin before the blank is entirely off it, it being necessary only that the blank be overbalanced sufficiently to prevent it from falling back into the mold.

The means for directly engaging and compressing the blank may consist of a mold and a coöperating die arranged for relative approaching and receding movement, the bottom of the mold being a plate of the character above mentioned, combined with mechanism for causing the plate to rise in the mold during the first portion, and to descend in the mold during the last portion, of the relative receding movement of the mold and die. Preferably the mold is mounted on a head which reciprocates vertically beneath a stationary die, the compressed blank discharging plate rising and falling in the mold during the descent of the head. The best form of mold of which I am aware is one which is laterally expansible and a feature of my invention consists in correlating with such a mold feeding mechanism arranged to deposit a blank in the mold during the expanding movement of the mold, and preferably approximately at the end of the expansion because the mold cavity is then open to its full extent.

The invention further relates to improved blank feeding mechanism for handling sole leather blanks. The blanks are usually supplied to the feeding mechanism singly by the operative and it is very advantageous that the feeding mechanism have as long a dwell as possible in blank receiving position, in order that the operative may have time easily to insert a blank in the feeding clamp, and that it be moved into and out of delivery position while the mold and die are separated sufficiently to avoid interference in the mechanism. It is, therefore, contemplated, as a part of the present invention, to provide means for causing the feeding clamp or device to move toward the mold during the last part of the separating movement of the mold and die and to move away from the mold during the first portion of their approaching movement. When the mold is carried on a reciprocating head, as previously described, the feeding movement will occur near the end of the descent of the head and the retraction of the feeding mechanism will take place in the first portion of the rise of the head. To the end that this mode of operation may be secured a

further feature of the invention consists in mechanism for operating the feeding devices which shall be capable of imparting to the latter a movement of considerable extent and rapidity without unduly straining the machinery or largely increasing the power required for its operation. A stationary cam has heretofore been used to effect the movement of the feed mechanism. According to the present invention a cam for effecting such movement is carried by a moving part of the machine and the combined effect of the movement of the cam and the movement of the mold relative thereto is utilized to secure the desired range and quickness of movement for the feed mechanism. By this arrangement it is possible to effect a feeding movement of considerable extent very quickly, permitting a long dwell of the feeding mechanism in blank receiving position. It is convenient and preferable to mount the cam upon one of the links of the toggle commonly employed for moving the compressing mold and such is the construction specifically described hereinafter, but it should be understood that the invention is not limited to such a specific construction, and that movement may be imparted to the cam in other ways.

In handling blanks such as are used in the manufacture of boots and shoes a very large variety of sizes and irregular shapes is encountered.

Another important feature of the present invention resides in feeding mechanism having provision for various adjustments to accommodate and place accurately in the machine blanks of various lengths, widths and shapes. The preferred construction includes a blank clamping or gripping device having means for engaging the edges of the blank. In order to locate the blank longitudinally of the feeding device so that it may be fed precisely to the desired position the provision of an end gage movable longitudinally of the feeding mechanism into a variety of adjusted positions is contemplated and a plurality of pairs of edge gripping fingers are combined with the end gage in order to locate the blank definitely and hold it securely. In the broadest aspect of this part of the invention however, it is not indispensable that the end gage and gripping fingers be combined in every case since it is within the scope of the invention to use one without the other. Preferably certain of the fingers engage the edges of the blank in front of its widest portion and means is provided for separating them sufficiently to drop the blank into the mold without opening the device wide enough to clear the widest part of the blank.

A further feature of the invention resides in a feeding mechanism which is constructed to release the foremost end of a blank prior

to the release of the rear end and which is timed to release the blank before the completion of its inward movement. With this construction the leading end of the blank drops before the end of the feeding movement is reached and engages the wall of the mold cavity so that the depositing of the blank accurately in the mold cavity is insured.

10 The automatic blank discharging mechanism is preferably actuated by movement of the mold and a novel feature of the invention comprises an improved switch mechanism for controlling the elevation and descent of the plate within the mold in the proper time relation to the movements of the mold.

When the discharging plate has considerable area its operation is uncertain if a single supporting spindle be depended on to guide and actuate it.

20 A further object of the present invention is to provide mechanism for supporting and actuating a plate forming the bottom of a compressing mold, which will be certain and accurate in its operation irrespective of the size of the plate being operated. This is of particular importance in a machine for compressing soles since the mold in such a machine is necessarily quite long and, especially in some of the larger men's sizes, the plate forming the bottom of the mold has considerable area and is quite heavy. According to the present invention the plate is preferably carried by a plurality of supporting members spaced apart to form a firm base for the plate to rest upon. For the purpose of ease and simplicity in securing exact, simultaneous timing of the supporting members it is preferable that they rest upon a single actuating device and this construction is illustrated in the specific embodiment of the invention upon which the following detailed description is based; but, while a single actuator is preferred, it will be understood that this is not essential to the success of the invention, it being only necessary that the supporting members be moved together in order to operate the plate accurately.

50 The operation of elevating the bottom of the mold to discharge the compressed blank is preferably performed automatically, although it is at times desirable to be able to give the elevating mechanism a range of movement different from that given it by the automatic mechanism, and to do this without operating the remaining mechanism.

Another feature of the invention, therefore, consists in the provision of automatic mechanism for discharging the compressed blank from the mold and additional manual means for operating the discharging means independently.

60 While, for purposes of illustration and explanation, a specific embodiment of the in-

vention is illustrated in the accompanying drawings and described in the following description, this should not be construed as a limitation of the invention which is more general in character and the scope of which is limited only as defined in the claims following the detailed description.

In the drawings: Figure 1 is a side elevation of a sole compressing machine embodying the present invention; Fig. 2 is a view showing the machine in front elevation; Fig. 3 is a longitudinal central sectional view of the compressing mold and blank discharging mechanism; Fig. 4 is a perspective view of a detail of the blank discharging mechanism; Fig. 5 is a perspective view of the compressing mold as seen from above; Fig. 6 is a perspective view of the blank feeding device with the cover removed to show the internal mechanism; Fig. 7 is a plan view of substantially the same mechanism shown in Fig. 6; Fig. 8 is a plan view of the adjusting mechanism for the blank feeding device; Fig. 9 is a sectional view on the line 9—9 of Fig. 8; and Fig. 10 shows a detail of an auxiliary clamping device for maintaining the adjustment of the blank feeding device.

Referring now to the drawings: A stationary frame 10 supports the moving parts of the machine. Power is transmitted from any suitable source of power, such as a belt 12, to a pulley 14 which is geared down through a system of gears 16 to a crank shaft 18. A cross head 20, guided for vertical movement in the frame 10, carries part of the compressing mold, the complementary part of which comprises a die supported by a stationary cross head 22 forming a part of the frame 10. A toggle 24, 26, having a lower stationary bearing at 28, is arranged to reciprocate the cross head 20 vertically. A connecting rod 30 connects the center of the toggle to the crank 32 upon the crank shaft 18. This mechanism is well known and forms no part of the present invention except in so far as it enters into combination with the features to be described hereafter.

A pair of mold slides 34, 36 is supported upon the upper surface of the cross head 20. The slides 34, 36 are connected by links 38 and 40 respectively to the stationary cross head 22 through adjusting devices 42. It will be apparent that as the cross head 20 rises and descends the mold slides 34, 36, will approach and recede from each other.

The side dies or sections 44, 46 of a divided compressing mold are carried by the mold slides 34, 36, respectively. The bottom of the mold is formed by a plate 48 which rests upon two supporting members 50, 52. The cross head 20 is chambered at 54 to permit the passage of an actuator bar 56 which is supported at its ends upon

rocker arms 58, 60. The rocker arms 58, 60 are pivotally mounted at 62 and 64 respectively in brackets 66, 68 secured to the cross head. The actuator bar 56 is so arranged 5 that the supporting members 50, 52 rest upon and are supported by it. Each of the supporting members 50, 52 consists of a horizontal bar 70 having a depending stem 72 which rests upon the bar 56 and a depending stem 74 which enters a suitable hole in the portion 76 of the cross head to prevent the supporting members from being turned 10 out of proper position.

With the construction described it will be 15 seen that when the arms 58, 60 are rocked the bottom plate 48 will be raised and lowered in the mold. This operation is effected by the mechanism shown in Fig. 4. The rock shaft 64 which supports the rocker arm 20 60 at its inner end carries at its outer end three radially projecting arms 78, 80, 82. A lug 84 projects laterally from the free end of the arm 82 and has its lower face beveled off at 86 to form a cam surface. Another 25 cam surface 88 is formed upon the outer corner of the lug 84. These two surfaces co-operate with a switch latch 90 which is pivoted at 92 upon an angle plate 93, which is 30 adjustably mounted upon a bracket 94 bolted to the frame of the machine. A spring 35 pressed plunger 96 tends to hold the latch 90 against a stationary stop 98. An adjustable stop screw 100 in the bracket 68 serves to limit downward movement of the 40 arm 78 and, consequently, of the actuator bar 56. In operation the stop screw 100 is so adjusted that when the arm 78 rests upon it the bottom plate 48 will be in its lowermost position, and the under face of the 45 lug 84 will be in position to engage the top of the switch latch 90 properly during downward movement of the cross head. Assuming the cross head 20 to be at the lower limit of its stroke, the relation between the various parts of the discharging mechanism will be substantially as shown in Figs. 3 and 50 4, the side sections of the mold being separated to the full extent of their movement and the plate 48 being lowered, the blank 55 having been introduced into the mold at the proper time by mechanism to be described hereinafter. As the cross head rises, the beveled face 88 of the lug 84 engages the switch latch 90 and pushes the latter aside. 60 During the last part of the rise of the cross head the lug 84 rises above the top of the latch 90 and the spring plunger 96 forces the latch beneath the lug in a direction which will be toward the right hand of an 65 observer facing the machine and stationed at the viewpoint from which the machine appears as illustrated in Fig. 4; the side sections of the mold close upon the blank, exerting pressure upon it laterally and, finally, the blank is compressed vertically.

between the plate 48 and the stationary die or follower 102. As the cross head descends the beveled under face 86 of the lug 84 rides over the edge 104 of the latch 90, causing the rock shaft 64 to be rocked in the proper direction to raise the actuator 56 and, through the supporting members 50, 52, the bottom plate 48, until the upper surface of the plate is flush with the top of the side sections of the mold, to permit the blank to 75 be ejected. This elevation of the bottom plate is nearly or quite completed during the first half of the descent of the cross head. During the last half of the descent of the cross head, and preferably near the end 80 thereof, the lug 84 slips off the latch, permitting the parts to resume their original position with the plate 48 at the bottom of the mold.

In order to permit the adjustment of the 85 angle plate 93 previously referred to, the bracket 94 is slotted at 95 and a screw 97, passing through the slot, is threaded into the angle plate. An adjusting screw 99 is also threaded into the angle plate and is 90 provided with a collar 101 which projects into a slot in the adjacent face of a projection 103 upon the bracket 94. By loosening the screw 97 the angle plate 93, with the switch latch 90 upon it, may be adjusted 95 accurately horizontally by means of the adjusting screw 99. The parts may then be secured in adjusted relation by tightening the screw 97. The purpose of this adjustment is to adjust the upper limit of the 100 movement of the plate 48, produced by the switch mechanism, so that the top of the plate shall come exactly flush with the top of the mold when a blank is being ejected.

The hand lever 80, which is rigid with the 105 rock shaft 64, may be manipulated whenever it may be desired to elevate the bottom plate within the mold without permitting the machine to go through its cycle of operations, as, for instance, when the molds 110 are to be changed.

The die 102 forming the top of the mold is secured to a block 110 which is guided for vertical adjustment by guides 112 secured to the upper stationary cross head 22. A wedge 115 114 has tongue and groove connections with the block 110 and the cross head 22. A screw 116, threaded into the wedge 114, has upon its outer end a hand wheel 118 and affords means for adjusting the wedge forwardly or rearwardly whereby adjustment of the block 110 and of the height of the die 102 carried thereby is effected.

Referring now to Figs. 6, 7 and 8, a feed 125 carriage 120 is mounted to slide to and fro upon the bracket 68. Racks 122 upon the under side of the feed carriage mesh with gears 124 (see Figs. 1 and 2) upon the ends of a shaft 126 which is journaled in the bracket 68. A pinion 128 upon the said 130

shaft meshes with a gear segment 130 upon the outer end of a lever 132 which is pivotally mounted at 134 in the bracket 68. The opposite end of the lever 132 carries a cam roll 136 which travels in a path 138 in a cam 140 secured to the lower toggle link 26. A material advantage is realized in mounting the cam 140 upon a moving part of the machine. In feeding a sole blank a large range of movement of the feed carriage is required and, by combining bodily movement of the cam with relative movement of the cam and cam roll, the necessary amount and quickness of movement can be secured without making the use of an unduly abrupt cam necessary. A pair of gripper arms 142 are pivoted at 144 to the feed carriage. The arms have forward extensions 146 upon which are mounted fingers 148 having their free ends 150 formed to engage the edges of the forepart of the sole in front of its widest part. The fingers are pivoted at 152 to split blocks 154 which embrace the extensions 146. Clamping screws 156, which pass through circular slots in the fingers 148, serve both to secure the fingers in adjusted position upon the blocks and to clamp the blocks to the extensions 146. A rear gage 158 is mounted upon a rack bar 160 sliding in suitable guides in the base of the feed carriage. The rack bar and rear gage are adjustable longitudinally of the carriage by means of a pinion 162 formed upon the lower end of the hollow shaft 164. A spindle 166 surrounded by a spring 168 passes through the hollow shaft and turns with the latter. An arm 170 upon the upper end of the spindle is provided with a depending pin 172 adapted to enter any one of a series of holes in an adjustment plate 174. A slot connection 176 between the arm 170 and the spindle 166 permits the pin 172 to be inserted in the holes of either one of two concentric rows, as shown in Fig. 8. These holes are so arranged that changing from one to another will adjust the rear gage 158 for any desired change in the size of the blanks being handled. The adjustment plate 174 is also capable of rotary adjustment about the shaft 164 as a center and is secured by a screw 178. This permits a finer degree of adjustment than is possible by the pin and hole arrangement alone. The spring 168 interposed between the head of the spindle 166 and the shaft 164 permits the spindle to be raised sufficiently to remove the pin 172 from the hole and the arm 170 to be turned as required. An additional clamping device 180 (see Fig. 10) embraces the rack bar 160 and is provided with a screw threaded stem 182 and a set nut 184. After the rear gage is adjusted the nut 184 may be tightened and the rack bar firmly secured. Two fingers 222 are geared together for equal and

opposite movement and pivotally mounted upon the rear gage 158 in proper position to engage the side edges of the rear portion of the blank. One of the fingers 222 is adjustably connected to one of the extensions 146 through a link 224 having a screw and slot connection 228 with a block 226 secured by a clamping bolt 227 for longitudinal adjustment upon the said extension. Pushers 186 for pushing off or ejecting a compressed blank from the machine to make room for the incoming blank being conveyed to the mold by the feed mechanism are pivotally mounted at the extreme ends of the extensions 146. Friction springs 188 surrounding the pivots tend to keep the pushers in any position in which they are left. A pair of stops 190 mounted upon the mold slides are arranged for engagement with projecting ears 192 upon the pushers and cause the latter to swing toward each other into the relation shown in Fig. 5 when the feed carriage is retracted. A pair of adjustable stops 194 at the opposite end of the mold slides are engaged by the ears 192 to cause the pushers 186 to move away from each other at the end of the advancing movement of the feed carriage.

A lever 196 is pivoted at 198 to the feed carriage and is connected by a link 200 to one of the arms 142. The arms themselves are interconnected to move equally and oppositely by means of links 202 and gear segments 204. A spring 206 is connected at one end to a hook 208 upon the feed carriage and at the other end to one end of the lever 196. The lever 196 carries at its opposite end a cam roll 210 which cooperates with cam projections 212 and 214, upon the bracket 68, to open the gripper arms approximately at the ends of the feeding and return movements of the feed carriage.

It will be apparent that in the feeding mechanism of the present invention provision is made for universal adjustment to accommodate a large range of sizes and shapes of blanks. This is of great advantage in handling blanks which occur in such a variety of sizes and shapes as do those used in shoe manufacture. The fingers 148 for gripping the forepart of the blank are independently adjustable both longitudinally and transversely of the device. The rear gage 158 and with it the fingers 222 are adjustable longitudinally of the holder and the fingers 222 are adjustable transversely independently of the fingers 148. Not only does this provide for adjustment to blanks of various sizes and shapes but it also allows the blank to be deposited accurately in the desired position.

The operation is as follows: Assuming the cross head 20 to be in its lowermost position, the arm 78 rests upon the screw 100 and the plate 48 rests in the bottom of

the mold. At this time the parts are in the position shown in Fig. 4, the grippers having been opened by the roll 210 riding upon the cam projection 212 and an uncompressed blank resting upon the bottom plate 48. As the crank 32 rotates, the toggle 26 is straightened and the cross head 20 rises. The combined effect of the forward movement of the cam 140 and the upward movement of the cam roll 136 relative to the cam is a quick outward movement of the feed carriage 120, during the initial portion of the rise of the cross head, the roll 210 riding upon the cam projection 214 at the end of such movement and the grippers being held open for the reception of a fresh blank, which is inserted in the feeding device by the operative. During the latter portion of the rise of the cross head the side sections 44, 46 of the mold exert lateral pressure upon the blank which is pressed heavily against the stationary die 102 at the end of the rise of the cross head. As the cross head begins to descend, the sole is relieved of vertical pressure and the side sections 44, 46 of the mold begin to open. Early in the descent of the cross head the face 86 of the lug 84 strikes the top of the latch 90, throwing the lever 82 forward and elevating the plate 48 in the mold until its upper face is flush with the top of the mold. The elevation of the plate is nearly or quite completed during the first half of the descent of the cross head, the compressed sole resting upon the plate being then in position to be engaged by the ends of the pushers 186 and ejected from the machine. The inward movement of the cam 140 and the downward movement of the roll 136 relative thereto during the further descent of the cross head effect a rapid inward movement of the feed carriage 120. This movement is so timed that the bottom plate will have been raised and the compressed sole resting thereon will be in position to be engaged by the advancing ends of the pushers 186, which engage and begin to push the compressed blank off the plate. The side sections of the mold continue to open during the descent of the cross head. During the last half of such descent, and preferably when the cross head is near the lower limit of its movement, the lug 84 passes below the face of the latch 90, the lever 78 falling until it rests upon the screw 100 and the plate 48 descending into the mold. The descent of the plate into the mold occurs very quickly and may begin as soon as the heavier portion of the compressed blank has been pushed off the plate, so that the blank will be sufficiently overbalanced to prevent it from falling back into the mold before the ejecting devices have ejected it from the machine. The mold is now open practically to its full extent, the plate 48 being in the bottom of the mold and

the mold cavity being ready to receive the incoming blank from the feed carriage. A short time before the feed carriage has completed its inward movement the roll 210 strikes the cam projection 212, opening the gripper fingers and releasing the incoming blank held thereby. The feeding movement of the sole blank being rapid, the blank has considerable momentum when the gripper fingers are opened to deposit it in the mold, and it has been found in practice that the entrance of the blank into the mold is best secured by having the upper surface of the plate 48 at least somewhat below the level of the tops of the side sections 44, 46; it being preferable that the said plate be in its lowest position, as above described. The plate having descended below the level of the tops of the side sections of the mold, the blank drops from the fingers of the feeding clamp. By reason of the fact that the fingers 148 are farther from the pivots 144 than the fingers 222, the advance end of the blank is released first, tending to drop before the other end drops and engaging the wall of the mold cavity so that the blank is located positively in the mold and cannot be misplaced.

It should be understood that the terms "blank" and "sole blank" used in the foregoing specification and the following claims are not limited in meaning to a blank of the exact shape or proportions shown in the drawings, but that the treatment of sole leather blanks of a variety of shapes and dimensions is contemplated.

Having described the invention, what is claimed as new and desired to be secured by Letters Patent is:—

1. A machine for compressing boot or shoe parts having, in combination, a hollow mold and a coöperating die, the mold being relatively movable toward and from the die, a plate normally forming the bottom of the mold cavity, but movable relatively to the mold, and means for causing the plate to rise relatively to the mold during the first part of the movement of the mold away from the die and to descend relatively to the mold during the last part of the movement of the mold away from the die.

2. A machine for compressing boot or shoe parts having, in combination, a hollow mold, a coöperating die, means for relatively moving the mold and die, an independently movable plate normally forming the bottom of the mold cavity, and means for actuating the plate to cause a compressed blank to be discharged from the mold during the first portion of the movement of the mold away from the die and for causing the plate to return to normal position during the last portion of the movement of the mold away from the die.

3. In a machine of the class described, the

combination of a hollow mold and a co-operating die, means for relatively moving the mold and die, an independently movable plate normally forming the bottom of the 5 mold cavity, and means for causing the plate first to move with the mold away from the die, then to rise relatively to the mold during the movement of the mold away from the die, then to descend relatively to the mold and then to move again with the mold relatively away from the die.

4. In a compressing machine, the combination of a vertically movable cross head, a hollow mold upon the cross head, a plate 15 movable vertically within the mold cavity, automatic mechanism for feeding a blank to the mold during the descent of the cross head, and means for raising the plate in the mold to discharge a compressed blank and 20 lowering it to receive another blank during the descent of the cross head.

5. In a machine for operating upon sole leather blanks, the combination of a mold, means for expanding and contracting said 25 mold laterally, a plate movable vertically within the mold to discharge a blank therefrom, and automatic feeding mechanism timed to feed a blank to and deposit it in the mold when the said plate is in the bottom 30 of the mold and the mold is expanded laterally approximately to its full extent.

6. In a machine for treating sole leather blanks for boots or shoes, the combination of a hollow mold, a movable plate normally 35 forming the bottom of the mold cavity, means for moving the plate vertically in the mold to discharge a blank therefrom and for then lowering the plate, and means for feeding another blank to the mold timed to deliver the blank to the mold when the said 40 plate is below the top of the mold.

7. In a compressing machine, the combination of a mold, a plate normally forming the bottom of the hollow mold cavity 45 and movable vertically within the mold to discharge a compressed blank therefrom, means for feeding a blank to the mold, and means for raising and lowering the bottom plate in the mold prior to the delivery of a blank by the feeding mechanism.

8. In a compressing machine, the combination of a mold, means for expanding and contracting the mold laterally, a plate normally forming the bottom of the mold 55 and movable vertically within the mold to discharge a blank therefrom, and means for raising and lowering the plate within the mold during the lateral expanding movement of the mold.

60 9. In a compressing machine, the combination of a mold, a plate movable within the mold to discharge a compressed blank therefrom, means for feeding a blank to the mold, and means for moving the plate to discharge a compressed blank from the mold

and for retracting the plate prior to the delivery of a new blank to the mold by the feeding mechanism.

10. In a compressing machine, the combination of an expandable mold, means for expanding and contracting the mold, means for discharging a compressed blank vertically from the mold, and means for operating and retracting the discharging means during the expanding movement of the 75 mold.

11. In a compressing machine, the combination of a mold, means for lifting a compressed blank vertically from the mold, means for feeding a blank to the mold, and 80 means for causing the lifting means to lift a compressed blank from the mold and for causing the lifting means to be lowered prior to the introduction of a new blank into the mold by the feeding mechanism.

85 12. In a compressing machine, the combination of a mold having a vertically movable plate normally forming its bottom, mechanism for feeding a blank to the mold, and means for raising the plate to discharge 90 a compressed blank from the mold and for lowering the plate during the feeding movement of said mechanism.

13. In a compressing machine, the combination of a mold having a vertically movable plate normally forming its bottom, mechanism for feeding a blank to the mold, and ejecting a blank from the mold, and 95 means for raising the plate to lift a compressed blank from the mold into the path 100 of the feeding and ejecting mechanism and for lowering the plate during the feeding movement of said mechanism.

14. In a machine of the class described, the combination of a mold having a vertically 105 movable plate normally forming its bottom, mechanism for feeding a blank to the mold, means for ejecting a blank from the mold, and means for raising the plate to lift a compressed blank from the mold into 110 the path of the ejecting means and holding the plate in raised position until the heavier portion of the compressed blank is removed from it, and for lowering the plate before the said blank is entirely removed from it. 115

15. In a machine of the class described, the combination of a mold having an independently movable plate normally forming its bottom, mechanism for pushing a blank off the plate, and means for causing the plate 120 to rise relatively to the mold to lift a compressed blank from the mold into the path of the pushing mechanism, then to remain in raised position until the heavier portion of the compressed blank is pushed off it and 125 then to start to descend relatively to the mold before the said blank is entirely pushed off.

16. In a machine of the class described, the combination of a mold having a vertically 130 movable plate normally forming its

bottom, mechanism for pushing a blank off the plate, and actuating mechanism for the plate arranged to cause it to be lowered quickly to normal position before the blank has been pushed entirely off the plate.

17. In a compressing machine, the combination of a mold having a vertically movable plate normally forming its bottom, mechanism for feeding a blank to the mold, and means for raising the plate to discharge a compressed blank from the mold and for lowering the plate before said mechanism has delivered another blank to the mold.

18. In a machine of the class described, the combination of a mold having a vertically movable plate normally forming its bottom, means for feeding a blank from a position at one side of the mold to a position above the mold and releasing the blank before its advance edge has come into vertical alignment with the corresponding portion of the mold, and means for raising and starting to lower the movable plate prior to the release of the blank by the feeding mechanism.

19. In a machine of the class described, the combination of a mold, and mechanism for feeding a blank endwise to the mold constructed and arranged to deliver the blank to the mold in a nearly horizontal position with the leading end of the blank lower than its rear end.

20. A machine for compressing boot or shoe parts having, in combination, a compressing mold and mechanism for feeding a blank to the mold comprising means for engaging the leading portion of a blank, means for engaging the rear portion of the blank, and mechanism for operating said means to release the advance portion of the blank prior to the release of its rear portion.

21. A machine for compressing boot or shoe parts having, in combination, a compressing mold and mechanism for feeding a blank to the mold comprising means for engaging the advance portion of a blank, means for engaging the rear portion of the blank, and mechanism for operating said means to release first the advance portion of the blank and then its rear portion prior to the completion of the feeding movement.

22. In a machine of the class described, the combination of a mold, a vertically movable plate normally forming the bottom of the mold, blank feeding mechanism arranged to deliver a blank to the mold with its leading end dropped below its rear end, and means for raising the plate to discharge a compressed blank from the mold and permitting the plate to descend below discharging position prior to the delivery of another blank by the feeding mechanism.

23. In a compressing machine, the combination of means for compressing a blank, including compressing dies, a reciprocating

head carrying one of the dies, a blank feeding device, and mechanism for causing the blank feeding device to move toward the compressing dies during the last portion of the movement of the head in one direction and away from the dies during the first portion of the movement of the head in the opposite direction.

24. In a compressing machine, the combination of relatively movable compressing dies, a reciprocating head carrying one of the dies, a blank feeding device, and mechanism for causing the blank feeding device to move toward the last-mentioned die during the last portion of the separating movement of the dies and to move away from it during the first portion of the approaching movement of the dies.

25. In a compressing machine, the combination of blank compressing dies, a vertically reciprocating head, blank feeding mechanism carried by the head, and means for advancing and retracting the feeding mechanism during the last portion of the descent and the first portion of the rise of the head.

26. In a machine of the class described, the combination of a compressing mold, feeding mechanism including devices for gripping the edges of an irregular blank in advance of its widest portion, and means for moving the feeding mechanism toward the mold and separating the gripping devices by an amount sufficient to drop the blank into the mold, but less than the greatest width of the blank, and for retracting the feeding mechanism in a plane above the blank.

27. In a sole compressing machine, the combination of a compressing mold, a feeding clamp having fingers for engaging the edges of a sole blank in advance of its widest portion, and means for imparting feeding movement to the clamp and separating the fingers by an amount sufficient to release the blank, but less than the greatest width of the blank, and for retracting the feeding clamp in a plane above the blank.

28. In a compressing machine, the combination of a mold, a plate forming the bottom of the mold, means for elevating the plate automatically to eject a blank from the mold and means for elevating the plate manually.

29. In a compressing machine, the combination of a mold, automatic means for ejecting a blank from the mold, and manually operable means for ejecting the blank.

30. In a compressing machine, the combination of a mold, mechanism for ejecting a blank from the mold, automatic means for actuating said ejecting mechanism, and manually operable means for actuating said mechanism.

31. In a compressing machine, the combi-

- nation of a mold, mechanism for ejecting a blank from the mold, an actuator for the ejecting mechanism, a plurality of parallel rocker arms upon which the actuator is supported and means, including a switch cam, for rocking one of said arms. 5
32. In a compressing machine, the combination of a movable mold, mechanism for ejecting a blank from the mold, and means, 10 including a plurality of rocker arms, for actuating the ejecting mechanism, said means being operated by movement of the mold. 15
33. In a device of the class described, the combination of a pair of fingers for gripping the edge of the forepart of a sole, a pair of fingers for gripping the edge of the heel portion of the sole and means for supporting said fingers in coöperative relation. 20
34. In a device of the class described, the combination of a pair of fingers for gripping the edge of the forepart of a sole, a pair of fingers for gripping the edge of the heel portion of the sole, and means connecting 25 said pairs of fingers, whereby the corresponding fingers of the two pairs are caused to move together in the same direction. 30
35. In a device of the class described, the combination of a pair of fingers for gripping the forepart of a sole, a pair of fingers for gripping the heel portion of the sole, and adjustable means connecting said pairs of fingers whereby the corresponding fingers of the two pairs are caused to move together in 35 the same direction. 40
36. In a device of the class described, the combination of a pair of fingers for gripping the forepart of a sole, a pair of fingers for gripping the heel portion of the sole, adjustable means connecting said pairs of fingers whereby the corresponding fingers of the two pairs are caused to move together in the same direction, and an adjustable gage for the rear end of the sole. 45
37. In a blank feeding device, the combination of a pair of gripper arms for holding a blank being fed, and a pusher pivotally mounted upon the forward end of each arm for engaging and pushing away a previously fed blank. 50
38. In a blank feeding device, the combination of a pair of gripper arms for holding a blank being fed, a pusher pivoted upon the forward end of each arm for engaging and pushing away a previously fed blank, and means for turning the pushers upon their pivots at the ends of the feeding and return movements of the device. 55
39. In a device of the class described, feed mechanism comprising a pair of gripper arms, pushing means at the forward ends of the arms, and means for causing said pushing means to bridge and to open the 60
- space between the arms at the beginning of the feeding and return movements, respectively, of the feed mechanism. 65
40. In a compressing machine, the combination of a mold, a plate forming the bottom of the mold and movable vertically therein to lift a blank from the mold, a plurality of supporting members for the plate, an actuator for the supporting members, and rocker arms carrying the actuator. 70
41. In a compressing machine, the combination of a mold, a plate forming the bottom of the mold and movable vertically therein to lift a blank from the mold, a plurality of supporting members for the plate, an actuator for the supporting members, rocker arms carrying the actuator, and means for 75 actuating the rocker arms. 80
42. In a compressing machine, the combination of a mold, a plate forming the bottom of the mold and movable vertically therein to lift a blank from the mold, a plurality of supporting members for the plate, an actuator for the supporting members, rocker arms carrying the actuator, and means for 85 actuating the rocker arms automatically. 85
43. A sole feeding device having a gage for the rear end of the sole, means for varying the location of the gage relative to the remainder of the device, and devices for engaging the side edges of the sole, so connected to the gage as to move with it when 90 its location relative to the remainder of the device is varied. 95
44. In a device of the class described, the combination of a pair of fingers for gripping the forepart of a sole, a pair of fingers for gripping the heel portion of the sole, adjustable means connecting said pairs of fingers, and an adjustable gage for the rear end of the sole connected to one of said pairs of fingers. 100
45. In a blank feeding device, the combination of an end gage for the blank, a rack bar upon which the gage is mounted, a pinion in mesh with the rack bar, means for adjusting the pinion and securing it in adjusted position, and edge grippers connected to the end gage. 105
46. In a machine of the class described, the combination of a movable cross head, a mold upon the cross head, a toggle for moving the cross head, feed mechanism for feeding articles to the mold, and a cam mounted upon one link of the toggle for operating the feed mechanism. 110

In testimony whereof I have signed my name to this specification in the presence of two subscribing witnesses.

THOMAS LUND.
